(57) **CLAIM**

The ornamental design for a gas-liquid separator as shown and described.

DESCRIPTION

1. Gas-liquid separator

1.1 : Front

1.2 : Back

1.3 : Left

1.4 : Right

1.5 : Top

1.6 : Bottom

1.7 : Perspective

1.8 : Perspective

Reproduction 1.1 is a front plan view of a gas-liquid separator showing my new design; reproduction 1.2 is a back plan view thereof; reproduction 1.3 is a left side elevational view thereof; reproduction 1.4 is a right side elevational view thereof; reproduction 1.5 is a top elevational view thereof; reproduction 1.6 is a bottom elevational view thereof; reproduction 1.7 is a right, front, top perspective view thereof; and reproduction 1.8 is a left, rear, top perspective view thereof; The broken lines in the drawings depict portions of the gas-liquid separator that form no part of the claimed design.
